UNITED STATES PATENT OFFICE.

THEODORE BAMBERG, OF BROOKLYN, NEW YORK.

JIG-SAW PUZZLE.

1,256,100.

Specification of Letters Patent. Patented Feb. 12, 1918.

Application filed May 21, 1917. Serial No. 170,016.

To all whom it may concern:

Be it known that I, THEODORE BAMBERG, a citizen of the United States, residing at Brooklyn, in the county of Kings and State 5 of New York, have invented certain new and useful Improvements in Jig-Saw Puzzles; and I do declare the following to be a full, clear, and exact description of the invention, such as will enable others skilled 10 in the art to which it appertains to make and use the same.

My invention relates to improvements in the class of amusement devices commonly known as jigsaw puzzles and the object is 15 to provide a number of cut out letters of the alphabet which may be used for spelling one or more words, when properly laid upon a flat surface and which may be assembled in the form of an animal or other character 20 when inverted.

With the foregoing general object in view, the invention resides in the device herein-after fully described and claimed, the descriptive matter being supplemented by the 25 accompanying drawing which constitutes a part of this application and in which:

Figure 1 is a perspective view of the puzzle assembled in the form of a donkey;

Fig. 2 is an elevation of the several sections of which the puzzle is made, showing them properly positioned for spelling a sentence.

In the drawing above briefly described, the numeral 1 designates a blank of wood, 35 cardboard, or other suitable material, said blank being shaped to produce the figure of an animal or any other desired subject. One side of the blank 1 is printed or painted to represent the animal in a life-like manner, 40 whereas the other side thereof will by preference be colored or decorated in some conspicuous manner.

The blank 1 is cut, by a jigsaw or the like into a plurality of sections 2 and 3, all of 45 said sections 2 being in the form of letters of the alphabet, whereas the sections 3 may be used for punctuating. In so far as possible, the several letters are completely sawed out, but as shown by the shading in 50 Fig. 2 and by the dotted lines in Fig. 1, it is often necessary to represent part of the outline by painting or in some other suitable manner. This is particularly the case with the letters O, D and R and would in most

cases be true of all letters having an opening of some sort formed therethrough, such as for instance as the letters A, B, P and Q. In all cases possible, however, it is preferable to completely outline the letter by the sawing operation.

The puzzle may be so made that numerous words or sentences may be spelled with the sections 2 when they are laid face down on a flat surface and although said sections are adapted to be assembled into the form of a donkey, in the puzzle illustrated, it will be obvious that we need not be restricted to any particular shape of the complete figure to be made by the removable sections.

From the foregoing, taken in connection 70 with the accompanying drawing, it will be seen that I have produced a puzzle which will afford considerable amusement and will at the same time be educational since the children are frequented with the letters in 75 unusual shapes and are thus more able to recognize any other letters when they appear in outline other than the common block type usually employed on children's blocks and the like. Furthermore, the spelling of 80 simple words is taught by the device.

I claim:

1. A puzzle comprising a flat figure cut into a plurality of sections in the forms of letters of the alphabet sufficient in number 85 to spell one or more words when the several sections are disassembled.

2. A puzzle comprising a flat blank painted or printed on one side to represent any suitable subject, said blank being cut into 90 a plurality of sections in the form of letters of the alphabet, said sections being sufficient in number to spell one or more words.

3. A puzzle comprising a blank cut in the outline of an animal and printed on one side 95 to represent such animal, said blank being cut into a plurality of sections in the form of letters of the alphabet, said sections being sufficient in number to spell one or more words.

In testimony whereof I have hereunto set my hand in the presence of two subscribing witnesses.

THEODORE BAMBERG.
